UNITED STATES PATENT OFFICE.

ALBERT G. DELMON, OF TAMPA, FLORIDA.

NECK-SHAVING GAUGE.

Application filed October 19, 1925. Serial No. 63,521.

This invention relates to tonsorial apparatus and has special reference to a gauge for shaving the neck which is herein called a neck shaving gauge.

As is well known it is almost impossible for a person to shave or trim the hair on his neck in an even manner and it is also extremely difficult for this to be done by another unless the person performing the work is a skilled barber. It frequently happens that persons are either compelled to shave their own necks or to have the shaving done by an unskilled person.

The principal object of the present invention is to provide an improved device to enable any person to properly and evenly shave his own or another's neck, the device taking the form of a gauge adjustable in size and position to any head and neck.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the device as applied to a man's head.

Figure 2 is a rear elevation thereof removed from the head.

Figure 3 is a partial rear elevation showing one modification.

Figure 4 is a partial rear elevation showing a second modification.

In the embodiment of the invention shown in the accompanying drawings there is disclosed a stiff head encircling band 10 adjustable to size by a buckle 11. From front to rear of this band runs a crown strap 12 provided with a buckle 13 by which the length may be adjusted. Thus these parts may be fitted to any head.

Carried by the rear of the head gear formed by these two members is a contour cutting gauge which may be of any desired form. For instance the gauge may be made of thin and stiff material such as celluloid

as shown at 14 in Figures 1 and 2, the lower edge 15 having any desired curvature. In a second form the gauge may be made of a length of wire 16 while in a third form the gauge may be made as in the first form but provided with a series of V-shaped slits 17. This latter form is used to obtain a tapering effect.

In the several forms the gauge is properly adjusted to the desired position on the neck, this being aided by adjustable fastenings which may be of any desired type but which, for illustration are here indicated as snap button parts 18 and 19, a plurality of pairs of such parts being used on either the gauge proper or the head band while a single pair of such parts is used on the other element. Then the neck is shaved to a line conforming to the lower edge of the gauge proper and, in the form shown in Figure 4, is either clipped or shaved along the slits 17.

It will now be seen that the device enables an unskilled person to shave or trim the hair on his own or another's neck with the same precision as though the work were done by a skilled barber.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

In a shaving gauge, a head band, a crown band having its ends connected to said head band, a contour gauge separate from and carried by the head band and adjustable relative thereto, means for detachably and adjustably connecting the contour gauge to said head band, and means to adjust the effective lengths of both the bands.

In testimony whereof I affix my signature.

ALBERT G. DELMON.
